UNITED STATES PATENT OFFICE

2,501,251

PAPER CONVEYER FOR PHOTOGRAPHIC
DEVELOPING DEVICES

Ernst Zollinger, Zurich, Switzerland

Application July 16, 1946, Serial No. 683,878.
In Switzerland July 30, 1945

9 Claims. (Cl. 271—2.1)

1

The present invention relates to a paper conveyor for photographic developing devices with several adjoining bath troughs such as for instance described in the Swiss Patent No. 168,749.

In these devices, of course, no conveyor can be used in which the paper sheets would be held continuously. The conveyor must be a separate one for each trough as otherwise the various baths would be soiled and mixed by the liquid carried by the conveyor, whereas on the transfer from one bath to the other liquid adhering to the paper must be removed as far as possible.

In the device according to the patent mentioned above chains passing over sprocket wheels and carrying pins extending perpendicularly to the plane of the paper are provided in each trough. However, the wet and slippery paper sheets are not seized at all by those driver pins if the pins are wrongly adjusted, or the sheets are damaged by piercing. The present invention overcomes this drawback.

The conveyor according to the invention is as regards its operation independent of any adjustment in that in every bath trough, at either side of the paper sheet, an elastic cord passing over an upper driving pulley and a lower reversing pulley and provided with pivoting driving members is arranged and the driving members exert a clamping action in the direction of the plane of the paper sheet so that they take the sheet with them and pass it between an upper reversing cylinder and four counter cylinders cooperating therewith for the purpose of transferring it into the next bath trough, and a supporting cylinder for the paper is arranged between the two pulleys at the top and also between the two pulleys at the bottom.

Due to this design the paper sheet is gripped at the edges and carried forward by the driving members by means of friction so that the driving members which are closely adjoining one another cannot fail to grip the paper nor can damage to the paper result due to it being pierced.

An embodiment of the invention is illustrated by way of example in the drawings, in which

Fig. 1 is a vertical section through a bath trough and the conveyor through the line 1—1 of Fig. 2 and the cylinders there shown;

Fig. 2 is a vertical section through the cylinders of the conveyor;

Fig. 3 is a view of a lateral guide plate and Fig. 4 of an intermediate guide plate;

Fig. 5 shows a section through the lateral guide plate along line V—V of Fig. 3,

2

Figs. 6 and 7 show two different views of a driving member on a larger scale;

Fig. 8 is a side elevation of the device according to the invention.

5 In the drawings the parts of the developing device not directly concerned with the object of the invention are illustrated only if they are absolutely necessary for the understanding of the invention, all other parts being omitted.

10 1 denotes the walls of the bath trough which together with a number of corresponding bath troughs are inserted in a row side by side in a common case 2 of which only the double wall on the driving side is shown. On top of this wall the 15 driving shafts 3 are supported, centrally arranged with respect to each bath trough. A sprocket wheel 4 is keyed on to each shaft 3, and all sprocket wheels are driven in the same direction of rotation by a common plate link chain. At the 20 left hand side of the wall 2 the crank arm 5 is keyed on the shaft 3. In the bath trough 1 near its end walls guide plates 6 are inserted which are held by threaded transverse rods 7 and which have the shape shown in Figs. 2 and 3. At the 25 top and the bottom bushes 8 are inserted in the plates 6, and the shaft 9 of the upper bearing cylinder 11 and the shaft 10 of the lower bearing cylinder 12 rotate in these bushes. Each of the cylinders 11 and 12 has a rubber coating and is of 30 a length corresponding to the width of the paper to be developed.

A driving pulley 13 is fixed on the upper driving cylinder shaft 9 on each side of the cylinder 11. The pulley 13 has a conical surface with a groove 35 13a of a semi-circular cross section and a collar or marginal portion 13b provided with axial grooves 13' around its circumference.

A reversing pulley 14 having a circumferential groove 14b with its bottom inclined inwardly is 40 fixed on the lower cylinder shaft on each side of the cylinder 12.

Both pairs of pulleys serve for the reception of the driving chain and the driving members 15 (Figs. 6 and 7). Each driving member has a 45 bush to which a pin 15a is laterally attached. The pin has a spherical extension 15b at its lower end and at its upper end an extension 15c inclined at an angle of about 30° on the bush side and a second extension 15d at an angle 50 of 90° to the first. The driving members lying alongside one another are joined to form a chain by means of an endless steel spiral wire 16 passing through the bores of their bushes, and they lie as can be seen from Fig. 1 on the circumference of the pulleys 13 and 14. On the upper 55

pulleys 13 the bushes of the driving members rest in the grooves 13a and the driving members lie on the collars upwardly inclined at an angle of about 30° with respect to the axes of the cylinders, so that the spherical projections 15b extend laterally beyond the collars. The extensions 15c of the driving members 15 then lie in the longitudinal grooves of the collars 13b so that the driving members are rotated by the pulleys. The bushes of the driving members 15 lie on the lower pulleys in the grooves 14b, and the driving members are upwardly inclined with respect to the axis of the cylinder at about 15° and the spherical projections extend beyond the rim of the pulley. Due to the slope of the bottom of the grooves 14b the driving members endeavour to slide inwards, i. e. towards the inner flange of the pulleys 14, under the pull of the wire spiral 16 and, accordingly, to clamp between themselves and to carry with them the paper sheet P whose edges are located approximately along the bisectrix between the two extensions 15c and 15d, as the sheet held between the bearing cylinder 12 and the intermediate plates 22 can not crumple or fold. As is to be seen from Figs. 2 and 3 guide rails 17 of U-shaped cross section are fixed on the inner side of each guide plate 6 by sheet iron strips 18; these guide rails extend below and up to the pulleys 13 and at their lower ends a little beyond the shaft of the lower cylinder, and they are divergent from top to bottom. The spherical extensions 15b slide within these guide rails, whereby the drivers when leaving the upper pulleys 13 are forcedly conveyed into the clamping position which they assume on the lower pulleys 14 so that they jam the paper sheets over the whole length of the guide rails and carry them along. In order that the spherical extension shall be properly engaged, the guide rails 17 are bent outwards at their ends and their flanges widened so that the spherical extensions 15b passing along the bent parts 17a of the guide rails transfer the driving members into the clamping position in which they remain for the whole length of the guide rails.

The intermediate guide plates 22 have a central cut away portion serving as a guide for the paper sheet, as can be seen from Fig. 4.

A pulley 18a is fixed on the upper cylinder shaft 9 outside the bath trough, and a link 19 in releasable engagement with the crank arm 5 is fixed on the pulley 18a. This pulley has also teeth 20 (Fig. 1) on its circumference.

The two outer guide plates 6 have upper extensions 6f (Fig. 2) between which a bearing frame 24 of U-shape is removably fixed by means of stay bolts 23 situated in slots. The shaft 25 of the reversing cylinder 26 is supported by the extensions 6f of the side plates and over it four counter cylinders 27 are supported by the bearing frame 24. The two outward cylinders are fixed and the two inner cylinders are movable upwards and downwards in radial slots. The drive for the reversing cylinder 26 is effected from the spur wheel 18a (Fig. 1) by means of a spur wheel 21 of double the size and having twice as many teeth, as the diameter of the reversing cylinder 26 is twice as great as the diameter of the pitch circle of the driver bush on the pulleys 13. The paper sheet P passing between the cylinder 26 and the counter cylinders 27 is carried forward by friction, squeezed at the same time and passes into the next bath trough. There it first passes between the vertical extensions 15d

whereby a lateral displacement is prevented, and the driving members 15 passing from the upper pulleys 13 and pivoted when entering the guide rails 17, clamp the paper sheet due to the fact that the distance between the two chains of driving members is smaller than the width of the paper when the driving members on the pulleys 13 have been swung into the clamping position, and this distance is maintained by the elastic tension of the spiral spring 16 during the further movement.

I do not limit my invention to the structure shown and described as modifications, within the scope of the appended claims, may be made without departing from the spirit of my invention. Having thus described my invention what I claim as new and desire to secure by Letters Patent is:

1. In a continuous treating device for photographic paper of the type having a plurality of independent bath troughs disposed side by side in parallelism, a paper drive roller in the upper portion of each trough and a paper travel reversing roller at the bottom of each trough, a pulley at each end of each roller and rotating therewith, two elastic cords, each cord forming a loop extending around the pulleys at the same side of the two rollers of one trough, and paper transport members pivotally strung on said cords, each of said members having a forked end receiving a side edge of the paper and exerting pressure on the paper in the direction of its plane and toward the longitudinal center line of the paper.

2. In a device as defined in claim 1, spaced guide plates disposed in each trough parallel to one another and at a right angle to the axis of rotation of said rollers, each of said plates having a marginal portion extending along the desired path of travel of the paper.

3. In a device as defined in claim 1, said transport members having a sleeve portion, and said elastic cord consisting of a spiraled wire extending through said sleeve portions.

4. In a device as defined in claim 1, said transport members having a sleeve portion through which said elastic cord extends, a stem portion connected tangentially with said sleeve portion and extending at a right angle thereto, a prong portion extending from said stem portion at an angle of substantially 30°, and another prong portion extending from said stem portion at substantially the same point as said first prong portion and at an angle of substantially 60°.

5. In a device as defined in claim 1, said transport members having a sleeve portion through which said elastic cord extends, a stem portion connected tangentially with said sleeve portion and extending at a right angle thereto, a prong portion extending from said stem portion at an angle of substantially 30°, and another prong portion extending from said stem portion at substantially the same point as said first prong portion and at an angle of substantially 60°, the pulleys at the end of the drive roller having a circumferential groove accommodating said sleeve portions and having a marginal portion provided with grooves extending substantially parallel to the axis of rotation of the pulley and adapted to receive one of said prong portions.

6. In a device as defined in claim 1, said transport members having a sleeve portion through which said elastic cord extends, a stem portion connected tangentially with said sleeve portion and extending at a right angle thereto, a prong portion extending from said stem portion at an

angle of substantially 30°, and another prong portion extending from said stem portion at substantially the same point as said first prong portion and at an angle of substantially 60°, the pulleys at the end of the reversing roller having a circumferential groove accommodating said sleeve portions and rim portions at both sides of said groove, the rim portion nearer the end of the reversing roller being of smaller diameter, said stem portion of said transport members resting on said rim portions and forming an angle of substantially 15° with the axis of rotation of the roller.

7. In a device as defined in claim 1, a shaft for each of said rollers and its adjacent pulleys, support members comprising channel means and being inserted in said troughs at the ends of, and supporting said shafts, said transport members having a sleeve portion through which said elastic cord extends, a stem portion connected tangentially with said sleeve portion and extending at substantially a right angle thereto and beyond said sleeve portion and into and being guided by said channel means.

8. In a continuous treating device for photographic paper of the type having a plurality of independent bath troughs disposed side by side in parallelism, a shaft in the upper portion of each trough, a paper drive roll connected with and driven by said shaft, a shaft at the bottom of each trough carrying a paper travel reversing roller, support members in each trough supporting the ends of said shafts and having an extension extending upward from one trough and to-

ward the adjacent trough, a second paper reversing roll supported by said extensions and being disposed above and between two adjacent troughs and parallel to said drive roller, a spur gear wheel connected with said first shaft, and another spur gear wheel having twice as many teeth as the first wheel connected with said second reversing roll and driving it at half the speed of said drive roll.

10. 9. In a device as defined in claim 8, a bearing frame supported by the extensions of the support members of one trough, two outer rollers rotatably supported by said frame and being disposed parallel to and adjacent said second reversing roller, and two inner rollers disposed substantially between said outer rollers and parallel to and adjacent said reversing roller and being supported by said frame rotatably and slidably in a direction substantially radial as to the axis of rotation of said second reversing roller.
